(57) **CLAIM**

The ornamental design for a scope, as shown and described.

DESCRIPTION

FIG. 1 is a perspective view of a first embodiment of the scope of our new design;

FIG. 2 is a right side elevation view of the scope of FIG. 1;

FIG. 3 is a left side elevation view of the scope of FIG. 1;

FIG. 4 is a top plan view of the scope of FIG. 1;

FIG. 5 is a bottom plan view of the scope of FIG. 1;

FIG. 6 is a rear elevation view of the scope of FIG. 1;
FIG. 7 is a front elevation view of the scope of FIG. 1;
FIG. 8 is a perspective view of a second embodiment of the scope of our new design;
FIG. 9 is a right side elevation view of the scope of FIG. 8;
FIG. 10 is a left side elevation view of the scope of FIG. 8;
FIG. 11 is a top plan view of the scope of FIG. 8;
FIG. 12 is a bottom plan view of the scope of FIG. 8;
FIG. 13 is a rear elevation view of the scope of FIG. 8;
FIG. 14 is a front elevation view of the scope of FIG. 8;
FIG. 15 is a perspective view of a third embodiment of the scope of our new design;
FIG. 16 is a right side elevation view of the scope of FIG. 15;
FIG. 17 is a left side elevation view of the scope of FIG. 15;
FIG. 18 is a top plan view of the scope of FIG. 15;
FIG. 19 is a bottom plan view of the scope of FIG. 15;
FIG. 20 is a rear elevation view of the scope of FIG. 15;
FIG. 21 is a front elevation view of the scope of FIG. 15;
FIG. 22 is a perspective view of a fourth embodiment of the scope of our new design;
FIG. 23 is a right side elevation view of the scope of FIG. 22;
FIG. 24 is a left side elevation view of the scope of FIG. 22;
FIG. 25 is a top plan view of the scope of FIG. 22;
FIG. 26 is a bottom plan view of the scope of FIG. 22;
FIG. 27 is a rear elevation view of the scope of FIG. 22;
FIG. 28 is a front elevation view of the scope of FIG. 22;
FIG. 29 is a perspective view of a fifth embodiment of the scope of our new design;
FIG. 30 is a right side elevation view of the scope of FIG. 29;
FIG. 31 is a left side elevation view of the scope of FIG. 29;
FIG. 32 is a top plan view of the scope of FIG. 29;
FIG. 33 is bottom plan view of the scope of FIG. 29;
FIG. 34 is a rear elevation view of the scope of FIG. 29;
FIG. 35 is a front elevation view of the scope of FIG. 29;
FIG. 36 is a perspective view of a sixth embodiment of the scope of our new design;
FIG. 37 is a right side elevation view of the scope of FIG. 36;
FIG. 38 is a left side elevation view of the scope of FIG. 36;
FIG. 39 is a top plan view of the scope of FIG. 36;
FIG. 40 is a bottom plan view of the scope of FIG. 36;
FIG. 41 is a rear elevation view of the scope of FIG. 36; and,
FIG. 42 is a front elevation view of the scope of FIG. 36.
